Fraser Kubasta PC; Elizabeth Philip Dahm; Kelly J.
Kubasta(57) **CLAIM**

The ornamental design for a chair, as shown and described.

DESCRIPTION

FIG. 1 is a front perspective view of a chair;
FIG. 2 is a front view of the chair of FIG. 1;
FIG. 3 is a rear view of the chair of FIG. 1;
FIG. 4 is a right side of the chair of FIG. 1;
FIG. 5 is a left side of the chair of FIG. 1;
FIG. 6 is a top plan view of the chair of FIG. 1; and,
FIG. 7 is a bottom plan view of the chair of FIG. 1.
The broken lines, when present in the drawings, are for the
purpose of illustrating the environment of the design and
form no part of the claimed design.
